D. P. FOSTER

Bit Stock.

N° 101,251.

Patented Mar 29, 1870.

United States Patent Office.

DAN P. FOSTER, OF WALTHAM, MASSACHUSETTS.

Letters Patent No. 101,251, dated March 29, 1870.

IMPROVEMENT IN BIT-STOCKS.

The Schedule referred to in these Letters Patent and making part of the same

To all whom it may concern:

Be it known that I, DAN P. FOSTER, of Waltham, in the county of Middlesex and State of Massachusetts, have invented certain new and useful Improvements in Bit-Stocks; and I do hereby declare that the following is a full and exact description thereof, reference being had to the accompanying drawings and to the letters of reference marked thereon.

The nature of my invention consists in arranging within the bit-socket a self-adjusting washer in such a manner that the shank of the bit will have more than one support, although it may not have been fitted expressly to this bit-stock; in other words, differently beveled shanks will be held steadily by my device.

It also consists in the method of attaching the head-piece.

To enable others skilled in the art to make and use my invention, I will proceed to describe its construction and use.

Drawings.

Figure 1 is an elevation of the bit-stock.

Figure 2 is a section of the same.

Figure 3 is an enlarged section showing the construction of the head-piece.

Figure 4 is an enlarged section of the shank-socket.

Figure 5 is a section of a part of the shank-socket as it appears when holding the bit.

I construct as follows:

The head piece B and foot piece E are made hollow, and bent as shown in figs. 1 and 2.

H and H' are screw-thimbles, which screw onto B and E, as shown in figs. 1 and 2.

The ends of B and E, upon which the screw-thimbles H and H' screw, are made slightly conical, and the tubes themselves slotted or cut longitudinally, so that by screwing up H and H' the caliber will be slightly lessened.

The two ends C and D of the crank-part F are bent, as shown in figs. 1 and 2, and slide into the hollow parts E and B, as shown, fitting loosely when the screws H and H' are but partially screwed on, but when the thimbles H and H' are screwed entirely on, they diminish the caliber of B and D sufficiently to hold C and E firmly.

O, figs. 1 and 4, represent a screw-thimble, which has an opening, Q, in its end, and an opening, V, on the side, so that when it is screwed out, as represented in fig. 4, the shank of the bit may be easily entered into the openings c and b, figs. 4 and 5. When the bit is thus entered the thimble may be screwed up so as to firmly hold it.

N', figs. 4 and 5, is a movable washer, having an orifice, b, somewhat smaller than the orifice c, so that, when the tapering shank of the bit is placed in position, as represented by dotted lines in fig. 5, the washer N' will yield sufficiently to allow the shank to fit itself to both orifices, c and b, and thus to be held true and firmly.

P is a spring acting against the washer N', to keep it in position.

A represents the head piece, and is connected to the upper end of the tube B by means of the bolt I and hollow screw-plug K, shown in fig. 3.

The bolt I has a head, I', and is free to revolve in K.

L is a cup-shaped washer, which serves a double purpose; first, it forms a part of and strengthens the head; second, it acts as a check-nut to hold the head firmly to the bolt I.

M is a screw-nut inserted in the wood-part A, which may be dispensed with in case A is made of metal.

In the drawing, fig. 3, L is shown at a little distance above K, but when in use L rests upon K.

For convenience in removing the head, an orifice, a, is made in the tube B, and a corresponding orifice, a', is made in the head I' of the bolt I, so that by inserting a pin, the bolt I will be prevented from revolving, in which case the head may be easily unscrewed.

What I claim as my invention, and desire to secure by Letters Patent of the United States, is—

1. The adjustable washer N' in combination with the holder N, working substantially as described, and for the purpose set forth.

2. The arrangement of the bolt I, the cup-shaped washer L, the screw-plug K and head A, constructed as shown and described, and for the purpose set forth.

D. P. FOSTER.
